CLAIM

The ornamental design for a skin patch for testing allergic reactions, as shown and described.

DESCRIPTION

FIG. 1 is an exploded perspective view of a skinpatch for testing allergic reactions, showing my new design; FIG. 2 is a top plan view thereof, the bottom being flat and unadorned;

FIG. 3 is a side elevational view thereof, the opposite side view being a mirror image; and,

FIG. 4 is an end view thereof, the opposite end view being a mirror image.

FIG. 2

FIG. 3

FIG. 4
